UNITED STATES PATENT OFFICE.

SHERMAN TAYLOR, OF WYMORE, NEBRASKA.

COMPOSITE RAILWAY-TIE.

1,231,669.

Specification of Letters Patent.

Patented July 3, 1917.

Application filed November 4, 1916. Serial No. 129,517.

To all whom it may concern:

Be it known that I, SHERMAN TAYLOR, a citizen of the United States, residing at Wymore, in the county of Gage and State of Nebraska, have invented a new and useful Composite Railway-Tie, of which the following is a specification.

This invention relates to composite railway ties, one of its objects being to provide a sectional tie made up of reinforced concrete, the sections being so shaped as to present their greatest weight and strength at the points subjected to the greatest strains, said sections being so assembled as to permit a limited amount of resiliency equivalent to that obtained by the use of the ordinary wooden ties.

A further object is to provide improved means for use in connection with the tie, whereby the rails can be securely fastened, it being possible readily to detach the rails when desired.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

35 In said drawings:—

Figure 1 is a view partly in elevation and partly in section of a tie embodying the present improvements, rails being shown fastened thereon.

40 Fig. 2 is a plan view of the structure shown in Fig. 1.

Fig. 3 is a perspective view of one of the reinforcing elements.

Referring to the figures by characters of reference 1 designates opposed like sections made up of concrete, each section being in the form of an elongated block having an intermediate flat bearing surface at the top thereof as indicated at 2 and downwardly 45 diverging upper surfaces 3 and 4 extending to the ends of the section. The bottom of each section is preferably substantially horizontal from the outer end thereof to a point under the bearing surface 2 and then is 55 preferably inclined downwardly and inwardly toward the other end of the section

as shown at 5. Embedded within the concrete section is a reinforcing rod 6 which, as shown in Fig. 3, is preferably bent to form an elongated loop 7 the crown portion of which is bent upwardly as at 8 while the ends of the loop merge into fingers 9 which overhang the loop and have upwardly extending stems 10 which project through the bearing surface 2. These projecting terminals are screw threaded so as to be engaged by nuts 11. Formed within the inner end of each section 1 is a recess 12 and when the two sections are oppositely disposed with their inner ends close to each other, the 70 recesses 12 are adapted to receive the end portions of a coupling pin 13 formed of steel or other suitable material. That portion of the pin between the sections 1 is adapted to be engaged by an eye 14 formed 75 at the lower end of an anchoring rod 15 which extends upwardly to and engages the middle portion of a tie bar 16.

Resting on each of the bearing surfaces 2 is a rail chair 17. The outer side of each 80 chair has a retaining lug 18 struck upwardly therefrom and bent inwardly so as to lap the outer base flange of a rail R. The threaded ends of the stems 10 are adapted to project through the chair at opposite sides 85 of the lug 18, as shown particularly in Fig. 2, the nuts 11 constituting means for fastening the chair to the tie section. The ends of the bar 16 are so shaped as to lap the inner base flanges of the rails R and this 90 bar is adapted to be fastened to the chairs 17 by bolts 19. The chairs extend inwardly beyond the inclined surfaces 3 of the sections 1 so that the bolts can be inserted readily into these projecting portions of the chair. 95

It is well known to those skilled in the art that ordinary wooden ties when in use, tend to break at three points. The weight of the load on the tie has a tendency to break the tie at the center and also at points directly 100 under the rail. The first break is due to the tendency of the tie to bend over the ballast under the center thereof as the ballast directly under the rails becomes packed. The breaks under the rails are due to the 105 wear upon the ties at these points and the packing of the road bed under the rails which results in the tie sagging directly under the rails and breaking. One of the 110 objects of the present invention, as before stated, has been to so construct the tie as to avoid these objections. The tie has been

made of considerable thickness and has been reinforced directly under the rails so that it will resist breakage at these points due to the weight of the loads passing over the tie. Should the tie sag at its ends due to the packing of the road bed thereunder, the sections will be free to shift relative to each other by reason of the steel connection 13 therebetween. At the same time the 10 inner ends of the tie sections will be anchored to the connecting bar 16 by the rod 15 so that the parts will not become displaced to an objectionable extent. Ballast may be placed over the inner portions of the tie sections and also under said sections as 15 ordinarily.

What is claimed is:—

1. A railway tie including opposed concrete sections, a pin anchored in the sections 20 and constituting a connection therebetween, a tie bar connecting the upper portions of the sections, and a connection between said pin and the tie bar.
2. A railway tie including opposed concrete sections converging downwardly toward each other, a pin anchored at its ends within the respective sections and constituting a connection therebetween, rail chairs secured upon the respective sections, a tie 25 bar connecting the chairs, and a connection between the tie bar and pin.
3. A railway tie including opposed concrete sections converging downwardly toward each other, a coupling pin anchored at 30 its ends within the respective sections, rail chairs mounted on the sections, reinforcing means embedded within the sections and detachably engaged by the chairs, a tie bar secured to said chairs, and a connection between the tie bar and coupling pin.
4. A railway tie including opposed con-

crete sections converging downwardly toward each other, a coupling pin anchored at 45 its ends within the respective sections, rail chairs mounted on the sections, reinforcing means embedded within the sections and detachably engaged by the chairs, a tie bar secured to said chairs, and a connection between the tie bar and coupling pin, said tie bar 50 constituting rail fastening means.

5. A railway tie including opposed concrete sections converging downwardly toward each other, a pin anchored at its ends within the respective sections and constituting a connection therebetween, rail chairs 55 secured upon the respective sections, and a tie bar connecting the chairs.

6. A railway tie including opposed concrete sections converging downwardly toward each other, a coupling pin anchored 60 at its ends within the respective sections, rail chairs mounted on the sections, reinforcing means embedded within the sections and detachably engaged by the chairs, and a tie bar secured to said chairs.

7. A railway tie including opposed concrete sections converging downwardly toward each other, a coupling pin anchored at 65 its ends within the respective sections, rail chairs mounted on the sections, reinforcing means embedded within the sections and detachably engaged by the chairs, and a tie bar secured to said chairs, said tie bar constituting rail fastening means.

In testimony that I claim the foregoing 75 as my own, I have hereto affixed my signature in the presence of two witnesses.

SHERMAN TAYLOR.
